US00D980838S

(12) **United States Design Patent** (10) **Patent No.:** **US D980,838 S**
Escolin et al. (45) **Date of Patent:** ** *Mar. 14, 2023

(54) **COMPUTING DEVICE**(71) Applicant: **Microsoft Corporation**, Redmond, WA (US)(72) Inventors: **Timothy G. Escolin**, Seattle, WA (US); **Young Soo Kim**, Bellevue, WA (US); **Scott Schenone**, Seattle, WA (US); **Panos Costa Panay**, Redmond, WA (US); **Ralf Groene**, Kirkland, WA (US); **Byungkwan Min**, Kirkland, WA (US)(73) Assignee: **Microsoft Corporation**, Redmond, WA (US)

(*) Notice: This patent is subject to a terminal disclaimer.

(**) Term: **15 Years**(21) Appl. No.: **29/707,912**(22) Filed: **Oct. 1, 2019**(51) LOC (14) Cl. **14-02**

Primary Examiner — Dana K Weiland*Assistant Examiner* — Russell Carnell Smith, Jr.(74) *Attorney, Agent, or Firm* — Banner & Witcoff, Ltd.(57) **CLAIM**

The ornamental design for a computing device, as shown and described.

DESCRIPTION

FIG. 1 is a perspective view of a computing device showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depicting the remainder of the computing device in FIGS. 1-7 show features that form no part of the claimed design.
